UNITED STATES PATENT OFFICE

ALEXANDER S. FEILD, OF PYOTE, TEXAS

OIL SAVER

Application filed March 2, 1928. Serial No. 258,629.

This invention relates to new and useful improvements in an oil saver.

One object of the invention is to provide a device of the character described specially designed to be used in connection with a cable tool drilling rig to prevent the escape and loss of oil from the well.

Another object of the invention is to provide an oil saver through which the drilling line works and which has a swiveling connection with the upper end of the well pipe or casing to the end that it will not be injured, bent, or distorted by the lateral swinging of the line as it is reciprocated by the walking beam through which it is operated.

A further feature of the invention is to provide a device of the character described through which the drilling line works and which forms a close fit with said line and with the well casing so as to prevent the escape of oil up through said oil saver and from the well.

A still further feature of the invention resides in the provision of a device of the character described which is of simple construction, may be cheaply and easily produced and readily applied to or detached from the well casing and drilling line.

With the above and other objects in view this invention has particular relation to certain novel features of construction, operation and arrangement of parts an example of which is given in this specification and illustrated in the accompanying drawings, where-

in:

Figure 1 shows a vertical sectional view of the device and associated parts,

Figure 2 shows a transverse sectional view thereof, taken on the line 2-2 of Figure 1, and

Figure 3 shows a plan view of the line clamp, showing the line in section.

Referring now more particularly to the drawings, wherein like numerals of reference designate similar parts in each of the figures the numeral 1 designates the well casing which is set in the well bore, and the numeral 2 designates a casing head which is reduced at its lower end, forming the inside annular

shoulder 3 having an annular groove 4 in its upper face.

The reduced lower end of the casing head is screwed on to the upper end of the casing 1.

Within the casing head there is a body 55 formed of the upper and lower sections 5 and 6, separably secured together by the stud bolts 7 whose lower ends are screwed into the lower section 6 and which extend up through the upper section 5 and whose upper ends are 60 threaded to receive the nuts 8. A suitable gasket 9 is interposed between the sections 5 and 6.

The facing sides of the sections of said body have the concaved recesses 10 and 11 which 65 register to form a spherical seat having the annular gaskets 12, 13, preferably of brass, seated in the respective sections 5 and 6, their inner surfaces conforming to the contour of 70 and flush with said spherical seat.

There is a tubular cylinder 14, preferably 75 formed of steel and having its mid portion formed into a ball joint member 15 which works in the spherical bearing formed between the sections 5 and 6. The lower end of this cylinder has an internal annular shoulder 16 against which the lower end of the cast iron, sectional cylinder liner 17, abuts. Threaded onto the upper end of the cylinder 17 and abutting the upper end of said liner 80 there is a flanged nut 18. The lower section 6, of the body, has an annular rib 19 which works in the groove 4 of the casing head.

There is a tubular steel plunger 20 which 85 works through liner 17 and has a ground joint fit therewith and this plunger extends down beneath the cylinder and works closely through and extends above the nut 18. Attached to the upper end of the plunger 20 there is a stuffing box 21 including the packing 22 held in the stuffing box by means of the gland 23, which is adjustably secured in place by means of the adjusting bolts 24. The operating cable 25 works 90 through the plunger 20 and is closely surrounded by the stuffing box packing 22 and which also works snugly through the flanged nut 26, which is threaded onto the lower end 95 of the plunger.

100

There is a line clamp formed of the up-standing box 27 carried by the stuffing box and in which are the clamp jaws 28, 28 one on each side of the line and one of which 5 may be operated by means of the shaft 29 which is threaded through the wall of the box 27 and whose inner end works against one of said jaws 28. By the operation of said shaft 29 the clamp jaws may be secured 10 around or released from the line 25.

The upper end of the operating line, or cable, 25 is attached to one end of the conventional walking beam 30. The usual cable tools (not shown) are attached to the lower 15 end of the line in the usual manner and for the usual purpose.

It is clear that as the end of the beam 30, to which the line is attached, swings upwardly, the line itself will move upwardly, and will 20 also swing laterally, but this lateral swing, or movement of the line will not have a tendency to bend, injure, or distort the plunger or the associated parts by reason of the fact that the cylinder, and plunger working there- 25 through, can swivel in the body of the device, and relative to the casing head, and at the same time there can be no leakage of oil either around the line, around the plunger, or around the ball and socket joint of the 30 cylinder. This last named joint may be lubricated through any type of oil cups, as 31.

The upper section 5, of the body, and the corresponding part of the casing head, have 35 the cooperating mutilated threads 32 by means of which the body may be secured in said casing head. If it be desired to remove the body and its attached parts from the casing head the screws 32 may be released by 40 giving said body a quarter turn and the body then lifted out. Sockets 33 are provided in the upper side of the body into either of which an upstanding pin may be inserted and a cable then attached to said inserted pin and 45 the body then turned, to release it, from a distance, without danger to the workmen.

It is sometimes necessary, during operations, to release the clamp jaws 28 from the line 25, and in the event of such release while 50 there is strong pressure in the well the plunger 20 will be prevented from blowing out by the engagement of the nut 26 against the lower end of the cylinder 14.

The parts above described may be made of 55 any suitable material and mechanical changes may be made in form or structure and equivalents substituted for the parts shown and I reserve the right to make such structural changes and substitutions as may be found 60 practical and such as may be comprehended within the scope of the appended claims.

What I claim is:—

1. The combination with a casing in a well, of a casing head attached to the upper end 65 thereof having an inside annular shoulder

provided with an annular groove, a two part body in said casing head having an annular rib in said groove and having an internal seat, a cylinder having a spherical enlargement thereon which conforms in shape to and works closely within said seat, a tubular plunger working through said cylinder, an operating line through the plunger, means for clamping the line to the plunger. 70

2. The combination with a casing in a well, 75 of a casing head attached to the upper end thereof, a two part body in said casing head having an internal seat, a cylinder having a spherical enlargement thereon which conforms in shape to and works closely within 80 said seat, a tubular plunger working through said cylinder, and forming close fitting joints with the upper and lower ends thereof, a liner in the cylinder around the plunger, upper and lower abutments carried by the 85 cylinder against which the ends of the liner abut, an operating line through the plunger, means for clamping the line to the plunger and means forming a fluid tight joint between 90 said line and plunger. 90

3. The combination with a casing in a well, a casing head attached to the upper end thereof, a body in said head, said body and head being provided, one with an annular rib and the other with an annular groove into which the rib fits, a cylinder mounted to swivel in the head and having a fluid tight joint therewith, a tubular plunger working through said cylinder a line working through and attached to said plunger, an external abutment 100 on the lower end of the plunger adapted to abut the lower end of the cylinder to limit the upward movement of the plunger. 100

4. A device of the character described including a casing head adapted to be connected to the upper end of a casing in a well, a body in said head having a socket bearing and formed of upper and lower sections detachably secured together, a cylinder having a ball joint member thereon which works in said bearing the lower end of the cylinder having an internal abutment liner in the cylinder whose lower end abuts said abutment, a nut threaded on to the upper end of the cylinder and abutting the upper end of said liner, a tubular plunger movable longitudinally through said cylinder, an external abutment on the lower end of the plunger beneath the cylinder, a stuffing box carried by the upper end of the plunger above the cylinder and formed to receive and closely surround an operating line and means connecting said line to said plunger. 110 115 120

5. A device of the character described including a casing head adapted to be connected to the upper end of a casing in a well, a body in said head having a socket bearing, a cylinder having a ball joint member thereon which works in said bearing the lower end of the cylinder having an internal abutment, 125

a liner in the cylinder whose lower end abuts said abutment, a nut threaded on to the upper end of the cylinder and abutting the upper end of said liner, a tubular plunger movable longitudinally through said cylinder, an external abutment on the lower end of the plunger beneath the cylinder and a stuffing box carried by the upper end of the plunger above the cylinder and formed to receive and closely surround an operating line, the upper end of the casing head, and the upper section of said body having intermeshing milled threads detachably securing said head and body together.

6. A device of the character described including a casing head, a body in said head having a socket bearing, a cylinder having a universal joint member thereon which works in said bearing, the lower end of the cylinder having an internal abutment, a liner in the cylinder whose lower end abuts said abutment, a nut threaded onto the upper end of the cylinder and abutting the upper end of said liner, a tubular plunger movable longitudinally through said cylinder, an external abutment on the lower end of said plunger beneath the cylinder and a stuffing box carried by the upper end of the plunger above the cylinder and formed to receive and closely surround an operating line, the upper end of the casing head, and the upper section of said body having interlocking means detachably securing the head and body together.

In testimony whereof I have signed my name to this specification.

ALEXANDER S. FEILD.
